Primary Examiner — Lauren D McVey

(57) **CLAIM**

The ornamental design for the function module, as shown and described.

DESCRIPTION

1. Equipment for distribution of electric power

FIG. 1.1: Perspective front view of a function module;

FIG. 1.2: Perspective rear view of the function module;

FIG. 1.3: Right view of the function module;

FIG. 1.4: Front view of the function module;

FIG. 1.5: Back view of the function module;

FIG. 1.6: Top view of the function module;

FIG. 1.7: Rear view of the function module;

FIG. 1.8: Left view of the function module.

1 Claim, 8 Drawing Sheets(56)
